Corinne P. Billings

UNITED STATES PATENT OFFICE.

GIRLANDO CONTRISCIANI, OF NEW YORK, N. Y.

CORNET.

Application filed August 30, 1921. Serial No. 496,912.

To all whom it may concern:

Be it known that I, GIRLANDO CONTRISCIANI, a citizen of the United States, and a resident of the city of New York, borough 5 of Manhattan, in the county and State of New York, have invented a new and Improved Cornet, of which the following is a specification.

The present invention relates to a musical 10 instrument and more particularly to a wind instrument of the type of cornets and similar instruments.

In the common type of cornets the effective length of the tube or tone column is 15 changed to produce changes in pitch, or intervals of the scale, by by-passing or inserting in the tube, tube sections of appropriate length. These tube sections are usually of the form of bends or "crooks" the end of 20 which connect with valve chambers in which are positioned hollow slideable pistons having ports for interconnecting the various "crooks" or bends in a manner governed by the positions of the various valves or pistons. Valve or piston instruments of this 25 type are, however, inferior to, or different in their tone or tone effects from instruments in which the changes in tone are produced by means of slides. However, the use of 30 slides in cornets and similar instruments in place of the common piston devices has heretofore not proven satisfactory in practice, owing largely to the difficulty of providing slides and actuating means sufficiently convenient and responsive to enable them to be 35 operated with the desired ease and facility.

An object of the present invention is to provide a compact and easily operated musical wind instrument in which changes 40 in tone intervals are produced by the operation of suitable slides.

Another object of the invention is to provide a musical wind instrument of simple construction in which the tone intervals of 45 the scale are obtained by the movement of slides arranged to be moved relatively unequal distances by a substantially uniform movement of the operating keys.

A still further object of the invention is to 50 provide a cornet or similar instrument having a key arrangement similar to that of the ordinary cornet, and adapted to produce the various notes of the scale by suitable slides actuated by said keys.

With these and other objects in view the 55 invention comprises the musical wind instrument described in the following specification and defined in the claims.

The various features of the invention are 60 illustrated in the accompanying drawings in which:

Fig. 1 is a plan view of a cornet embodying a preferred form of the invention, parts of the instrument being broken away to more clearly show the slide operating mechanism. 65

Fig. 2 is a side elevation of the cornet shown in Fig. 1, a portion of the instrument being shown broken away to more clearly show the slide operating mechanism.

Fig. 3 is a cross sectional view taken on 70 line 3—3 of Fig. 1, and,

Fig. 4 is a detailed view of a portion of the key mechanism.

In the present invention the instrument is formed of a number of fixed tube sections 75 which are alternately connected at their opposite ends by means of slides telescoping in said sections to form a single connected tube. The various tones of the scale are produced by reciprocating the slides in the fixed tube 80 sections, the degree of reciprocation of individual slides being adjusted to produce different changes in pitch corresponding to the different tone intervals. The movement of the slides is obtained by means of a key 85 and lever mechanism positioned on the fixed tube sections intermediate of or between opposite slides in a position similar to the keys or pistons of the ordinary cornet. The lever mechanisms of the different sets of 90 slides and keys are proportioned to give the desired degree of unequal movement of the slides for a uniform movement of the keys.

Referring more particularly to the accompanying drawings the tube portion of the 95 cornet is composed of a number of sections 10 in the form illustrated, four fixed in a substantially parallel relation with each other by suitable braces or other connecting means and connected in succession by means of movable slides 12, 14 and 16 each pair of tubes being connected together at one end only and two successive slides being connected to any one tube, one slide at one end of said tube and the other slide at the other 100 end of said tube, to form a single continuous tube extending from a mouth-piece 18 to a bell 20. The slides 12, 14 and 16 extend

within the fixed tube portions 10 in a telescopic relation and freely slide or reciprocate outwardly and inwardly in the fixed tube sections for relatively different distances adjusted to produce the desired tone interval.

The movement of the slides 12, 14 and 16 is obtained through the operation of corresponding keys 22, 24 and 26 preferably mounted in a frame 28 carried by means of 10 supporting arms 29 on the fixed tube sections 10 in substantially or approximately the position normally occupied by the pistons or keys in the ordinary type of cornet. The pistons are normally held in their uppermost position by means of springs 30, 32 and 34, which surround guides 36, 38 and 40 for the keys and are confined between a lower edge 42 of the frame 28 and collars 44, 46 and 48 carried on the stems of the 15 pistons 22, 24 and 26 respectively.

When the keys 22, 24 and 26 are depressed the corresponding movement is transmitted to the slides 12, 14 and 16 by means of lever mechanisms arranged to give the desired 20 movement. To this end the collars 44, 46 and 48 are connected by means of connecting links 50, 52 and 54 respectively to arms 56, 58 and 60 of bell crank levers 62, 64 and 66 which are pivoted on the lower part of the 25 frame 28. The other arms 68, 70 and 72 of the bell crank levers are pivotally connected by means of rods or links 74, 76 and 78 to the slides 14, 12 and 16 respectively. The 30 position of the bell crank lever 62 is the reverse of the levers 64 and 66 and the levers operate in such a manner that as the keys 22, 24 and 26 are depressed the corresponding levers are rotated to move the slides 14, 12 and 16 outwardly from the fixed tube sections of the cornet. When the keys are released they are returned to their upper position by means of the springs 30, 32 and 34 and the slides are again withdrawn into the 35 fixed tube sections.

In the normal operation of the instrument the keys 22, 24 and 26 are depressed to substantially equal distances as in an ordinary cornet. The relation between the lever arms of the bell crank levers 62, 64 and 66 40 is, however, such that for an equal displacement or movement of the keys there is an unequal movement of the tubes for each movement of the keys, the length of the movement of each slide being adjusted to 45 produce the different tone intervals of the scale. This is accomplished by having the lever arms 56, 58 and 60 of equal, or substantially equal, lengths and making the arms 68, 70 and 72 of unequal lengths and proportional 50 to the lengths of movement of the slides or connecting tubes. Thus, in the particular embodiment illustrated in the drawings, the arm 68 is longer than the arm 72 and the arm 72 is longer than the arm 70. The keys may of course be operated in units 55

of 2 or 3 in the usual manner to produce a greater extension of the effective length of the tube for the production of tone intervals not obtained by the movement of individual slides. The operation of the keys is preferably arranged so that the different tones of the scale are produced by the same fingering as in the ordinary piston cornet.

The degree to which the slides are moved toward the tube sections is, however, subject 75 to the control of the player who may decrease the throw of the lever mechanism by depressing the keys 22, 24 and 26 to less than their lowermost position. In a similar manner all three keys may be interconnected 80 by means of a notched plate 80 shown in detail in Fig. 4 having notches 82, which fit corresponding grooves 84 in the keys 22-26. When the plate 84 is in position on the keys 22-26 all three keys are moved simultaneously and the different tone intervals are obtained by depressing the keys to a greater or less extent.

To permit the instrument to be tuned, the 85 ends of the rods 74, 76 and 78 are threaded as at 86 and are connected to the slides 12, 14 and 16 by means of nuts 88 threaded on the rods 74-78 and enclosing ears 90 mounted on the respective slides. Through this arrangement the effective length of the rods 95 74-78 may be adjusted to tune the instrument.

Through the above described invention a cornet or similar musical instrument is provided in which the various tone intervals 100 may be obtained by operating keys arranged in a similar position and relation as in the ordinary cornet thereby avoiding the necessity of changes in fingering in changing from the old to the present instrument. The 105 tone of the instrument is entirely under the control of the player and the desirable tone effects of a slide instrument are obtained. A further control of the operation of the 110 playing of the instrument is also obtained through the interconnection and partial movement of the several keys to give notes not obtainable by an ordinary piston instrument. Instruments may, according to the 115 present invention, also have the advantages of greater simplicity and ease in manufacture and are less liable to get out of order and out of tune. It is obvious that a larger number of slides and pistons may be used than those shown in the drawings and that 120 other changes in the form of embodiment of the invention may be made without departing from the broader features of the invention.

Having thus described my invention what 125 I claim as new and desire to secure by Letters Patent is:

1. A musical wind instrument having in combination fixed substantially straight, parallel tube sections, slides connecting said 130

- tubes in succession, each pair of tubes being connected together at one end only and two successive slides being connected to any one tube, one slide at one end 5 of said tube and the other slide at the other end of said tube, and means positioned intermediate said slides arranged to move said slides independently on said fixed tube sections.
- 10 2. In a musical wind instrument the combination of fixed substantially straight parallel tube sections, slides connecting said tubes in succession, each pair of tubes being connected together at one end only and two successive slides being connected to any one tube, one slide at one end of said tube and the other slide at the other end of said tube, and a mechanism positioned intermediate opposite slides for independently moving 15 said slides relatively unequal distances.
3. A musical wind instrument having in combination fixed substantially straight, parallel tube sections, slides connecting said tubes in succession, each pair of tubes being connected together at one end only and two successive slides being connected to any one tube, one slide at one end of said tube and the other slide at the other end of said tube, keys positioned intermediate said opposite 20 slides and mechanism operated by said keys for independently moving said slides.
4. In a musical wind instrument the combination of fixed substantially straight, parallel tube sections, slides connecting said tubes in succession, each pair of tubes being connected together at one end only and two successive slides being connected to any one tube, one slide at one end of said tube and the other slide at the other end of said tube, 25 a frame work mounted intermediate said opposite slides and mechanism mounted on said frame work for moving said slides individually.
5. In a musical wind instrument, the combination of fixed substantially straight, parallel tube sections, slides arranged alternately at opposite ends of said tube sections and connecting said tube sections in succession, keys mounted transversely of said fixed 30 tube sections and means connecting said keys to said slides to operate said slides individually.
6. In a musical wind instrument the combination of fixed substantially straight, parallel tube sections, slides connecting said tubes in succession, each pair of tubes being connected together at one end only and two successive slides being connected to any one end only, and two successive slides being connected to any one tube, one slide at one end of said tube and the other slide at the other end of said tube, 35 keys positioned intermediate said successive slides, mechanism operated by said keys for individually moving said slides and means for interconnecting said keys to cause said keys and slides to move in unison.
7. In a musical wind instrument, the combination of fixed substantially straight, parallel tube sections, slides connecting said tube sections, operating keys movable transversely of said fixed tube sections, bell crank levers, connecting links between the levers at one of their ends and the keys and connecting links between the levers at the other of their ends and the slides. 40
8. A musical wind instrument having in combination a tube portion formed of fixed substantially straight, parallel tube sections and connecting slides telescopically slidable on said fixed sections, a frame mounted on said fixed tube sections, keys mounted on said frame and a lever mechanism connecting said keys individually to said slides to move said slides relatively unequal distances 45 upon a uniform movement of said keys.
9. In a musical wind instrument having in combination a tube portion formed of fixed substantially straight, parallel tube sections and connecting slides telescopically slidable on said fixed sections, a frame mounted on said fixed tube sections, keys mounted on said frame transversely of said fixed tube sections, bell crank levers pivoted on said frame, connecting means between the levers at one of their ends and the keys and connecting means between the levers at the other of their ends and the slides. 50
10. A musical wind instrument having in combination fixed substantially straight, parallel tube sections, slides connecting said tubes in succession, each pair of tubes being connected together at one end only and two successive slides being connected to any one tube, one slide at one end of said tube and the other slide at the other end of said tube, operating means positioned intermediate said slides to move said slides independently on said fixed tube sections and means for interconnecting said operating means to cause said slides to move in unison. 55
11. A musical wind instrument having in combination substantially straight, parallel tube sections, slides connecting said tubes in succession, each pair of tubes being connected together at one end only and two successive slides being connected to any one tube, one slide at one end of said tube and the other slide at the other end of said tube, 60 keys positioned intermediate said successive slides, mechanism operated by said keys for individually moving said slides and means for interconnecting said keys to cause said keys and slides to move in unison.
12. In a musical wind instrument, the combination of fixed substantially straight, parallel tube sections, slides connecting said tube sections, operating keys mounted on said fixed tube sections, bell crank levers mounted in proximity to said keys, connect- 65

ing links between the levers at one of their ends and the keys and connecting links between the levers at the other of their ends and the slides and means for adjusting the effective length of said last named links between said slides and said lever ends.

In witness whereof, I have hereunto set

my hand at the borough of Manhattan, city and State of New York, this 29 day of Aug., 1921.

10

GIRLANDO CONTRISCIANI.
